CURTAIN OPERATING MECHANISM

Thomas W. Holt and John F. Levan, Elkhart,
Ind., assignors to Excel Curtain Company, Elkhart, Ind., a corporation of Delaware

Application February 6, 1934, Serial No. 709,984

12 Claims. (Cl. 156—28)

This invention relates to mechanism for raising and lowering curtains from a point remote from the curtain or window and particularly mechanism for raising and lowering the back window 5 curtain of a motor vehicle from the driver's seat and has for its object a particularly simple mechanical operating means as distinguished from an electrical, and the location of the operating parts thereof relative to the window opening or 10 frame.

It further has for its object an arrangement of a curtain mechanism including two members, one of which is a winding roller, with any suitable means for operating it, which members extend 15 parallel to each other and spring means acting upon the other member, and the relative arrangement of these members to the window opening.

It also has for its object an equalizing spring 20 acting through any suitable operating mechanism on the roller in opposition to spring means to neutralize or counterbalance, wholly or partly, the influence of the spring means on the roller, so that the mechanism acts easily and with minimum 25 operating effort. It further has for its object a curtain mechanism of the same general type, wherein the spring actuated member or spring means may be either a spring roller or a batten strip at one end of the roller with spring means 30 acting on opposite ends of the batten strip.

It further has for its object a curtain mechanism in which the spring actuated member is a spring roller on which the curtain is wound, the curtain having spaced apart strips or tapes or 35 runners, preferably located at the opposite side edges of the curtain and extending across opposite ends of the window frame and winding on the actuator roller, which may be actuated in any suitable manner.

It further has for its object a manually operated mechanism for operating the actuating roller and including a screw member extending axially of the roller and connected thereto through nut means to rotate the same in one direction or the other upon axial movement of the screw member, the screw member or some part connected thereto, extending axially beyond one end of the roller, where it is connected to mechanism, which is operated by the operator.

Other objects will appear throughout the specification.

The invention consists in the novel features and in the combinations and constructions herein-after set forth and claimed.

In describing this invention, reference is had to 55 the accompanying drawings in which like char-

acters designate corresponding parts in all the views.

Figure 1 is an elevation of one embodiment of this curtain mechanism, the same being shown as applied to the rear wall of an automobile body, which is shown fragmentarily, the seat-back of the rear seat of the vehicle being removed.

Figure 2 is a vertical sectional view, taken approximately on line 2—2, Figure 1, the operating mechanism including connections extending to 15 within reach of the driver's seat being also shown.

Figure 3 is an enlarged longitudinal fragmentary sectional view through the actuating roller.

Figures 4 and 5 are enlarged sectional views taken respectively on lines 4—4, 5—5, Figure 3. 15

Figures 6 and 7 are views similar to Figures 1 and 2 of another embodiment of our invention.

Figure 8 is an enlarged sectional fragmentary view through the batten strip at one end of the roller and the contiguous portion of the spring 20 means and housing acting on each end of the batten strip.

The chief use of a curtain mechanism of this character is in automobiles to lower the rear curtain from the driver's seat to shut off the rays 25 from headlights of cars following close behind and also at times to cut off horizontal rays of the sun when coming through the rear window.

We have shown our invention as embodied in an automobile body construction. 30

1 designates the rear wall structure of the body of an automobile, which wall is formed with a window framing 2. 3 is the glass pane in the window opening and 4 designates the usual back of the rear seat. 5 designates the floor of the car; 35 6 the dash, and 7 the instrument board strip.

This invention comprises a curtain mechanism including two members extending parallel to each other, one being an actuating roller extending along one of the window frame members, as 40 the lower horizontal frame member and the other member being spring actuated and acting on the curtain and tensioned by the operation of the roller, when the roller is rotated in one direction, and acting on the curtain when the 45 roller is turned in the opposite direction and operating means for actuating the roller in one direction or the other, this means including mechanism, which is self-restraining, in order that the curtain may remain in any of its operated positions, and also an equalizing spring 50 acting in opposition to the spring means acting on the curtain, in order to partly or wholly counterbalance the spring means, so that the mechanism operates with minimum effort, both 55

when power operated or when embodying the operator-operated feature of this invention.

In Figures 1 and 2, 11 designates the operating roller and 12 the spring actuated member which 5 is a spring roller. The actuating roller is mounted in suitable brackets 13 and 14 secured to the rear wall frame or the window framing, the roller 11 extending along the lower edge of the window opening, and the mechanism to be presently described being located within the seat 10 back 4 and concealed thereby and below the frame member 2^a against which the seat back rests at its upper edge. The roller 12 is supported by suitable brackets 15 and set in the 15 rear wall structure 1 above the upper sill of the window frame 2, and the free end of the curtain is connected to the roller 11 by strips, tapes or runners 16 which wind on the roller 11. These tapes 16 extend along or lap the upright members 20 of the window frame. As the construction and operation of a spring curtain roller is very old in the art, a description and illustration of such a spring curtain roller is thought to be unnecessary.

25 It is obvious that upon winding of the roller 11 in one direction, the tapes 16 will be wound thereon and the curtain unwound from the spring roller 12 and brought down across the window opening and then upon unwinding of the roller 11, the spring roller will react and rewind the curtain thereon.

30 In Figure 6, the spring actuated member instead of being a spring roller is a batten tube or strip 17 secured in any well known manner to the upper end of the curtain and it is spring actuated by springs 18 thrusting against pins or 35 trunnions 19 extending beyond the ends of the tubular batten strip and overlapping the vertical window frame members. The springs 18 are housed in suitable guides 20, as tubular guides, 40 extending lengthwise of the vertical members of the window frame at opposite lateral sides of the window opening and having brackets 21 at their ends which are secured to the window frame. The springs at their upper ends thrust against 45 heads or plungers 22 which slidably fit the tubular guides 20 and which in turn thrust against the pins 19. The pins extend through lengthwise slots 23 in the guides 20 and have rounding 50 heads 24 which coact with the spring thrust heads 22.

55 In operation, when the actuating roller is rotated in one direction, the curtain will be wound thereon and pulled down against the action of the springs 18 and when the roller is moved in the opposite direction, the springs 18 will react and lift the batten strip. In either form of the invention shown in Figures 1 and 6, the curtain mechanism includes two members, one of which 60 is an actuating roller and the other a spring actuated member, either a spring roller or a spring actuated batten strip.

65 As seen in Figure 3, the actuating roller 11 is rotated in one direction or the other by a reciprocating actuator including a slide and screw means operated by the slide, said actuator being movable axially of the roller. The slide extends 70 axially beyond one end of the roller 11, and the projecting end is connected to a prime mover. The roller 11 is mounted in any suitable manner at one end in the bracket 14 and at its other end is mounted on a stationary tube 25 fixed in the bracket 13, the roller having spaced apart bearings at 26 and 27 on the tube, and the screw means consists of a strip having its opposite end

75 portions 28 and 29 twisted spirally in opposite directions, the end portion 29 extending into the tube 25 and being connected by a swivel joint 30 to the slide 31, which extends beyond the end of the roller and through the bracket 13. The spiral end portion 28 coacts with nut means, as a suitable slot or opening 33 formed in a head 34 fixed in the roller 11, and the spiral end portion 29 coacts with nut means at the inner end of the tube 25, here shown as provided by the opposite straight branches of a U-shaped element or staple 35 extending through the inner end of the tube 25. As the pitches of the end portions 29 and 28 are opposite to each other, it is obvious that a maximum rotary movement 15 will take place upon a minimum endwise sliding movement of the sliding actuator 31, as the spiral strip and roller 11 are rotated in opposite directions during the axial endwise movement of the slide and screw.

20 The actuator 31 is operated from within reach of the driver's seat and as here shown, it is actuated through a motion transmitting element or lever, as an angle lever 40 pivoted at its angle at 41 to a suitable supporting plate 42 secured 25 to the window frame, one arm of the lever being connected at 43, as by a pin-and-slot connection, to the sliding actuator 31 and the other arm being connected to one end of a push-and-pull wire 45 which extends through a suitable tubular 30 guide 46 to a handle 47 mounted in the instrument board strip 7. The wire 45 and its guide 46 constitute frictionally engaged members which act to restrain rotation of the roller 11 under the influence of the spring actuated roller or 35 spring actuated batten strip.

50 50 is the equalizing or counterbalancing spring, heretofore referred to, to ease the operating effort. This spring acts in opposition to the spring of the spring roller 12 or the springs 18. As here 40 shown, the equalizing spring acts on the lever 49.

As here illustrated, the equalizing spring 50 encircles a rod 52 which is pivoted at 53 to the plate 42 and slides through a block 54 swivelled to one arm of the lever 40, the spring thrusting 45 at one end against a shoulder or nut 55 on the rod, and at its other end against the block 54.

55 In Figure 1, the equalizing spring is under greater compression when the curtain is up or open. Hence, when the lever 40 is operated to wind the roller 11 and tensions the spring of the spring roller 12, the spring 50 boosts the operator's effort and when the lever 40 is actuated to raise or open the curtain at which time, the spring of the roller 12 reacts, the spring 50 again 55 acts in opposition to the curtain spring preventing violent reaction and sudden winding up of the curtain and relieves the operator of doing more than merely move the handle 47.

60 In Figure 6, when the lever 40 is operated to lower or close the curtain against the action of the springs 18, the spring 50 boosts the effort of the operator and when the lever 40 is operated to turn the roller 11 to permit the springs 18 to react and close the curtain, the spring 50 re- 65 strains violent reaction. Thus, the equalizing spring causes the curtain mechanism to work smoothly with little effort on the part of the operator.

70 What we claim is:

75 1. A window curtain mechanism including two members spaced apart and a curtain extending between said members, the curtain being secured at its opposite ends to said members, one of said members being a roller and the other of said

- members being spring actuated and stressed by the winding of the roller when the roller is actuated in one direction and operating means for rotating the roller in opposite directions.
5. 2. A window curtain mechanism including two members spaced apart and a curtain extending between said members, the curtain being secured at its opposite ends to said members, one of said members being a roller and the other of said members being spring actuated and stressed by the winding of the roller when the roller is actuated in one direction and operating means for rotating the roller in opposite directions, said operating means including frictionally engaged members to restrain turning of the roller under the impulse of the spring actuated member.
3. A window curtain mechanism including two members spaced apart and a curtain extending between said members, the curtain being secured at its opposite ends to said members, one of said members being a roller and the other of said members being spring actuated and stressed by the winding of the roller when the roller is actuated in one direction and operating means for rotating the roller in opposite directions, the operating means including an equalizing spring acting thereon in opposition to the action of the spring actuated member.
4. A window curtain mechanism including two members spaced apart and a curtain extending between said members, the curtain being secured at its opposite ends to said members, one of said members being a roller and the other of said members being spring actuated and stressed by the winding of the roller when the roller is actuated in one direction and operating means for rotating the roller in opposite directions, the operating means including an equalizing spring acting thereon in opposition to the action of the spring actuated member and frictionally engaged members to restrain turning of the roller under the impulse of the spring actuated member.
5. A window curtain mechanism including two members spaced apart and a curtain extending between said members, the curtain being secured at its opposite ends to said members, one of said members being a roller and the other of said members being spring actuated and stressed by the winding of the roller when the roller is actuated in one direction and means for operating the roller in opposite directions, the operating means including an actuator extending axially of the roller within the same and movable axially thereof and one end of the actuator extending beyond one end of the roller, and operator-actuating means including a motion transmitting element connected to the actuator outside of the roller.
6. A widow curtain mechanism including two members spaced apart and a curtain extending between said members, the curtain being secured at its opposite ends to said members, one of said members being a roller and the other of said members being spring actuated and stressed by the winding of the roller when the roller is actuated in one direction and means for operating the roller in opposite directions, the operating means including an actuator extending axially of the roller within the same and movable axially thereof and one end of the actuator extending beyond one end of the roller, operator-actuating means including a motion transmitting element connected to the actuator outside of the roller, and an equalizing spring acting on the actuator to act in opposition to the spring actuated member.
7. A curtain mechanism including rollers carried by the frame along opposite edges of the window opening, one of the rollers being spring actuated, a curtain winding thereon and having spaced apart runners connected to the other roller to wind thereon, and operating means for rotating the other roller in opposite directions, said operating means including friction mechanisms for preventing rotation of the other roller under the influence of the spring roller, whereby the curtain remains in any one of its operated positions.
8. In a structure having a window opening and a window frame, a curtain mechanism including rollers carried by the frame along opposite edges of the window opening, one of the rollers being spring actuated, a curtain winding thereon and having spaced apart runners connected to the other roller to wind thereon, and operating means for rotating the other roller in opposite directions, said operating means including frictionally engaged members, one slideable relative to the other, for restraining rotation of the other roller under the influence of the spring roller and an equalizing spring acting through said operating means on the other roller in opposition to the spring of the spring actuated roller, whereby the curtain remains in any one of its operated positions.
9. In a structure having a window frame enclosing a window opening, a curtain mechanism including two spaced apart members extending parallel to each other, one member being an actuator roller extending along one of the window frame members and the other being movable across the window opening toward and from the roller, a curtain connected at its opposite ends to said members and winding on and unwinding from the roller, spring means carried by the frame along the sides of the frame at an angle to said members and adjacent the window opening, said spring means thrusting against the ends of said other member, and operating means for actuating the roller in one direction to wind the curtain thereon against the action of the spring means and in the other direction to permit the spring means to react and unwind the curtain.
10. In a structure having a window frame enclosing a window opening, a curtain mechanism including two spaced apart members extending parallel to each other, one member being an actuator roller extending along one of the window frame members and the other being movable across the window opening toward and from the roller, a curtain connected at its opposite ends to said members and winding on and unwinding from the roller, spring means carried by the frame along the sides of the frame at an angle to said members and adjacent the window opening, said spring means thrusting against the ends of said other member, and operating means for actuating the roller in one direction to wind the curtain thereon against the action of the spring means and in the other direction to permit the spring means to react and unwind the curtain, and an equalizing spring acting through the operating means on the roller in opposition to the spring means.
11. In a window curtain operating mechanism, the combination of a hollow rotary winding roller having supports therefor, one of said supports comprising a stationary tube extending into the roller from one end thereof and the roller having bearings on the tube, whereby the roller rotates about the tube, mechanism for rotating the roller

including an actuator comprising a slide slidable in the tube and projecting beyond one end of the same, and screw means connected to said slide and movable axially therewith and connected to the roller within the same to rotate the same, and nut means fixed to the roller for translating the axial movement of the screw means into a rotary movement of the roller when the actuator is actuated in one direction or the other, and an operating member and motion transmitting connections between the operating member and the actuator including a member connected to said projecting end of the actuator.

12. In a window curtain operating mechanism, the combination of a hollow rotary winding roller having supports therefor, one of said supports comprising a stationary tube extending into the roller from one end thereof and the roller having bearings on the tube, whereby the roller rotates about the tube, mechanism for rotating the roller including an actuator comprising

ing a slide slidable in the tube and projecting beyond one end of the same, and screw means connected to said actuator and movable axially therewith, and nut means fixed in the roller and coacting with the screw means for translating the axial movement of the actuator into a rotary movement to the roller when the actuator is actuated in one direction or the other, the screw means being rotatably connected to the actuator and including a screw portion and a nut therefor within the tube and said screw portion coacting with the nut of the tube, the screw portion being of opposite pitch from said screw means whereby when the actuator is moved axially, the screw means and the roller rotate in the same directions, thus causing the maximum rotation of the roller upon a minimum axial movement of the actuator, and means connected to the actuator to operate it.

THOMAS W. HOLT. 20
